(57) **CLAIM**

The ornamental design for a touch screen, as shown and described.

DESCRIPTION

FIG. 1 is a front, right, top perspective view of a touch screen showing our new design in a first state with the screen horizontal;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view of the touch screen in a second state with the screen vertical;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right, top perspective view of the touch screen in a third state with the screen angled;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The broken lines depict portions of the touch screen that form no part of the claimed design.

1 Claim, 21 Drawing Sheets
